UNITED STATES PATENT OFFICE.

MATSUSHITA KOSAI, OF NEW YORK, N. Y.

METALLIC SHEET.

Application filed October 29, 1925. Serial No. 65,694.

My invention relates to soft, pliable, metallic sheets capable of being fixedly attached to a material surface by means of heat and pressure.

5 The object of my invention is a process for producing a soft, pliable metallic sheet, such as gold, silver, bronze or other substance, which may be fixedly attached to a material, such as a fabric, by means of heat 10 and pressure, resulting, in a compounded material of a soft, pliable nature from which the metallic sheet can not be separated by use, a further object of my invention being the products produced by my 15 process.

It is evident that artistic and valuable results can be obtained if such metallic sheets can be fixedly attached to fabrics with the retention of softness and pliability, and that 20 this value can be enhanced if the method of application is one which can be easily performed without the employment of intricate and expensive machinery.

My device has all of the above mentioned 25 and other valuable features, in that it can be fixedly attached to fabrics by means of heat and pressure, such as may be obtained from a heated flat iron.

It is evident that this means of attachment will enable the user to cut out any 30 desired shapes of the metallic sheets and to arrange them in any desired design, the thus formed design being fixedly attached to the fabric by applying a heated iron.

35 I have found that these desirable qualities of pliability and ease of application can be obtained from a thin pliable metallic foil having attached to its face a film of rubber, such attachment being accomplished by a 40 pliable binder such as gun-cotton or other suitable material.

I have found it advantageous at times to add softening agents such as glycerine and gum and I prefer to use these although 45 I do not limit myself to their employment.

In Figure 1, 1 represents the gelatine glycerine and gum arabic mixture, 2 represents the foil of metallic material, 3 represents the solution of gun-cotton, gums and camphor, and 4 represents the india rubber and wax.

In Figure 2, 2 represents the foil of metallic material, 3 represents the gun cotton, gums and camphor and 4 represents the india rubber.

I give the following as examples of modified methods of carrying out my process.

1. I make a weak aqueous solution of gelatine, glycerine and gum arabic and pour it into a shallow flat dish and when it has 60 evaporated to a thick consistency, I place a foil of metallic material, such as sheet gold or sheet silver, thereon, allow to almost dry, remove the foil with the attached film, dry and press. I then produce an acetone 65 solution of gun-cotton, gum copal, gum sandarac and camphor and apply a thin sheet of this solution, preferably by means of a brush, to the coated side of the metallic foil, and dry. I then apply a thin foil of india 70 rubber and wax dissolved in carbon tetrachloride to the treated side of the metallic foil and dry. I prefer to apply pressure during the last treatment in order to make a uniform film sheet and to produce adherence 75 between the rubber sheet and the treated side of the metallic foil.

2. I dissolve rubber in carbon tetrachloride, flow it into a thin sheet and dry. To one 80 side of this, I then apply a thin coating, or film, of gun-cotton, gum copal, gum sandarac and camphor dissolved in acetone, and when nearly dry, I place a thin metallic foil to the prepared side, a sheet of tissue paper over the metallic sheet, apply gentle and 85 uniform pressure and dry.

It will thus be seen that my device comprises a thin metallic foil to one face of which is attached a film of gun-cotton and gums, and to this latter film is attached a 90 thin film of rubber.

If, now, this device be placed upon a material, such as fabric, with the rubber side in abutment with the material, and heat and pressure be applied to the exposed surface, 95 as, for instance by means of a hot iron, the rubber becomes soft and permanently affixed to the material, thus presenting, in the case of a fabric, a soft, pliable material having a permanently affixed metallic face surface.

I do not limit myself to the particular number, materials, times, temperatures or steps of procedure as particularly mentioned herein, as these are given simply as a 100 means for clearly describing my invention.

What I claim is:—

1. As an article of manufacture a soft, pliable metallic sheet capable of being fixedly attached to a material surface by 110

means of heat and pressure comprising a soft, pliable metallic foil, a film of gun-cotton attached thereto and a film of rubber attached to the first mentioned film.

2. As an article of manufacture a soft, pliable metallic sheet capable of being fixedly attached to a material surface by means of heat and pressure comprising a thin sheet of gelatine attached to one face

10 of a soft, pliable, metallic foil, a thin film of gun-cotton attached to the face of the gelatine sheet and a thin film of rubber attached to the gun-cotton film.

3. As an article of manufacture a soft, pliable metallic sheet capable of being fixedly attached to a material surface by means of heat and pressure comprising a thin sheet of gelatine and glycerine attached to one face of a soft, pliable, metallic foil, a thin film of gun-cotton attached to the face of the gelatine-glycerine sheet and a thin film of rubber attached to the gun-cotton film.

4. As an article of manufacture a soft,

pliable metallic sheet capable of being fixedly attached to a material surface by means of heat and pressure comprising a thin sheet of gelatine, glycerine and gum attached to one face of a soft, pliable, metallic foil, a thin film of gun-cotton attached to the face of the gelatine-glycerine-gum sheet and a thin film of rubber attached to the gun-cotton film.

5. As an article of manufacture a soft, pliable metallic sheet capable of being fixedly attached to a material surface by means of heat and pressure comprising a thin sheet of gelatine, glycerine and gum attached to one face of a soft, pliable, metallic foil, a thin film of gun-cotton and gum attached to the face of the gelatine-glycerine-gum sheet and a thin film of rubber and wax attached to the gun cotton film.

Signed at New York city in the county of New York and State of New York this 28th day of October, 1925.

MATSUSHITA KOSAI.
